UNITED STATES PATENT OFFICE.

WILMOT LAKE, OF WASHINGTON, DISTRICT OF COLUMBIA, ASSIGNOR OF ONE-THIRD TO AUSTIN HARVEYCUTTER AND ONE-THIRD TO HERBERT A. WRENN, OF WASHINGTON, DISTRICT OF COLUMBIA.

BASE-BALL GAME-BOARD.

1,112,919.

Specification of Letters Patent.

Patented Oct. 6, 1914.

Application filed October 25, 1913. Serial No. 797,194.

To all whom it may concern:

Be it known that I, WILMOT LAKE, a citizen of the United States, residing at Washington, in the District of Columbia, have invented certain new and useful Improvements in Base-Ball Game-Boards, of which the following is a specification.

This invention relates to game boards and especially to the game of base ball having the nature or character of the plays displayed on a board and designated by a rotatable pointer mounted central of the board.

The object of the invention is to provide 15 a base ball dial having such arrangement and comprising such indications of plays as to furnish therein every action or play and the result thereof possible in an actual game upon a field.

20 A further object of the invention is to provide a base ball game board having nine sections arranged in circular form with respect to nine combined strike and ball intervals between the sections, and to cluster 25 or group all possible plays or base ball game actions and results in the combined sections and intervals.

A still further object of the invention is 30 to provide a base ball game board with means for indicating, on any one section thereof, all plays in which the player of that section may take part, and under certain conditions, to have certain plays on the part of other players in connection with said 35 player indicated on or by the same section.

A still further object of the invention is 40 to provide a base ball game dial wherein the result of each action of the ball will be indicated by a single movement of one and the same indicator hand, so that there may 45 be no false movement of the indicator, and every stop of the indicator will indicate some part or parts of an actual base ball game.

45 In the accompanying drawings forming part of this application: Figure 1 is a plan view of the dial board. Fig. 2 is a sectional view of the dial and the pointer or indicator hand. Figs. 3 to 11 inclusive are detail plan views of the various sections of the 50 dial. Fig. 12 is a perspective view of the boards closed. Fig. 13 is a plan view of a base ball field.

The same reference characters denote the

same parts throughout the several views of 55 the drawings.

In carrying out my invention I employ a board or a pair of boards 1 and 2 hinged or foldable at 3. The board 1 has the ball field 1^a depicted thereon, and colored circles 4, 5 and 5^a for counting balls, strikes and outs respectively by placing ordinary disks over said circles according to the strikes and balls occurring in each inning. The board 2 has depicted thereon the playing dial, and the pointer or indicator hand 6 is revolutely mounted central of the dial by means of a pivot 7. The hand 6 is preferably stamped out of thin sheet metal and has a central depression 8 for the pivot 7, 70 and end depressions forming contacts 9 for engaging the dial face of the board 2, so as to afford as little friction as possible between the hand and said face.

The playing dial is composed of nine sections 10, representing the requisite number 75 of players in a base ball team. Said sections 10, are separated by nine combined ball and strike spaces 11. The strike spaces being proportioned to equal one third of the spaces 80 11. The sections 10 are composed of a cluster of spaces denoting every base ball play possible in an actual base ball game and when taken in connection with the spaces 11, the dial will represent every resulting movement 85 of a base ball in actual play and the particular player or players taking part in a play or plays, and the same is indicated by the indicator hand coming to rest after revolving it in either direction. The foul 90 spaces 12 for third base, first base, right and left fields are placed as they actually are on a ball field, and the catcher section or cluster has a foul space 13.

In order to obviate any false movement 95 or lost play on the board in the stopping of the hand at impossible plays or results I provide each of the clusters or sections 10, with an alternative foul space 14, and each cluster or section is provided with an error 100 space 15 which is divided into three parts 14^a for indicating the character of an error such as ground ball missed, fly ball missed, and wild throw.

All the "outs" of every character what- 105 soever are noted in the dial sections 10, and such player or players as assist in the outs will be shown by the indicator hand

stopping at one or another of the small spaces 16. The "fly caught" space 16^a is divided in part, into two spaces 17 for indicating whether such "fly caught" is a long or short fly.

A set of guide rules will be furnished with each board to assist in playing the game, and for arriving at the percentage of each player.

It will be observed that in the event of the 10 indicator hand stopping at any play or ball action noted in the sections 10, which, by reason of the position of the player or players, it is impossible, at certain stages of the game, to make, the proposition will be provided for 15 in the error spaces. The position of the batter and base runners are changed by placing the usual disks on the home plate and on the bases of the diamond shown in Fig. 13, and then moving these disks according to the 20 indication of the dial hand in stopped position, and by moving such figures as directed by the indicator hand stopping at the section spaces or at the spaces intervening the said sections, the game may be played strictly in 25 accordance with an actually played base ball game, and every detail and feature of an actual game is indicated or produced in this apparatus.

Upon reference to the drawings it will be 30 found that all plays possible for a particular player are grouped in one section with the designation of the player making the play; and that each section is sub-divided into apportionate related plays so as to indicate the 35 principal play and all relative plays simultaneously.

It will be seen that whatever play or plays which may occur from every ball pitched to the batter, as in an actual field game, are 40 provided for in the dial; and that a game may be scored and the average of each participating player determined as in an actual ball game.

I do not wish to be understood as limiting 45 the invention in the matter of the divisions and sub-divisions of the dial sections as they may be varied as desired according to the development of the game, nor do I wish to confine myself to any particular size or material in the practical production of the invention.

Having thus described my invention what I claim as new and desire to secure by Letters Patent is:—

55 1. In a base ball game board, a dial di-

vided into sections so as to apportion the dial with one section for each participating player of a team, apportionate play spaces grouped in each section and showing plays pertaining to that player, proportionate ball and strike spaces between said sections, and an indicator hand mounted on the dial.

2. In a base ball game board, the combination of apportionate sections grouped in dial form and representing each player of 65 a participating team, each section containing indicia designating the plays of each player, and apportionate ball and strike spaces separating said sections.

3. In a base ball game board, a dial depicted thereon and composed of apportionate player sections alternated with apportionate intervals for balls and strikes, said sections comprising relatively apportionate play spaces showing such plays as are possible by 75 the player of a certain section together with assists to said player on the part of some other section player, and a suitable dial hand for indicating the plays.

4. In a base ball game board, the combination of a base ball diamond delineated on one portion of the board, a dial depicted on the other portion of the board and composed of alternate player sections and ball and strike intervals, said sections having grouped 85 therein relatively apportionate play spaces so that any one of the sections will show a principal play and a relative play simultaneously, and an indicator hand central of 90 the dial.

5. In a base ball game board, a single dial having apportionate denotations and a dial hand showing the result of every pitched ball and simultaneously showing the player or players participating in the movement of 95 the ball.

6. In a base ball game board having an indicator hand, circular sections denoting each player and having grouped radial lines forming spaces for denoting the plays of a certain player and the player assisting such plays by one and the same movement of the indicator hand.

In witness whereof I hereunto set my hand in the presence of two witnesses.

WILMOT LAKE.
